UNITED STATES PATENT OFFICE.

HIRAM W. HAYDEN, OF WATERBURY, CONNECTICUT, ASSIGNOR TO HOLMES,
BOOTH & HAYDEN, OF CONNECTICUT.

DESIGN FOR A SPOON OR FORK.

SPECIFICATION forming part of Design No. 15,129, dated July 8, 1884.

Application filed April 7, 1884. Term of patent 7 years.

To all whom it may concern:

Be it known that I, HIRAM W. HAYDEN, a citizen of the United States, residing at Waterbury, in the county of New Haven and State of Connecticut, have invented and produced certain new and useful Improvements in a Design for Spoons, Ladles, and Forks; and I do hereby declare the following to be a full, clear, and exact description of the invention, such as will enable others skilled in the art to which it appertains to make and use the same, reference being had to the accompanying drawing, forming part thereof.

The drawing shows a face or plan view of a spoon, the handle of which shows my ornamental design, the leading features of which consist in the shank or smaller portion of the

handle (from a to a') being ornamented in imitation of hammered silver, and the broader portion b having a sprig upon a contrasting ground upon its upper side or face.

What I claim is—

The design for a spoon, ladle, or fork herein shown and described, the same consisting of the ornamentation in imitation of hammered silver on the smaller portion of the handle, and the sprig on the broader portion, substantially as shown and described.

In testimony whereof I affix my signature in presence of two witnesses.

HIRAM W. HAYDEN.
